HOUSING FOR AN ELECTRO-MECHANICAL TRANSDUCER

Jerry O'Brien, 33 Pamrapo Ave.,
Jersey City, N.J. 07305

Continuation-in-part of abandoned design application Ser. No. 454,222, Mar. 25, 1974. This application May 27, 1975, Ser. No. 580,815

Term of patent 14 years

Int. Cl. D14—03

U.S. Cl. D26—14 A

FIG. 1 is a perspective view of a housing for an electro-mechanical transducer;

FIG. 2 is a top plan view;

FIG. 3 is a front elevation; and

FIG. 4 is a side view thereof.

This application is a continuation-in-part of design application Ser. No. 454,222 filed on Mar. 25, 1974, for voice transducer with funnel and now abandoned.

I claim:

The ornamental design for a housing for an electro-mechanical transducer, as shown and described.
